Samuel J. Holtzman, 8201 Symphony Drive,
Baltimore, Md.

Filed Oct. 17, 1963, Ser. No. 77,023

Term of patent 14 years

(Cl. D50—7)

FIG. 1 is a top plan view of a luggage lock or similar article embodying my new design;

FIG. 2 is a side elevational view thereof;

FIG. 3 is an end view looking toward the left side of FIG. 1; and

FIG. 4 is an end view looking toward the right side of FIG. 1.

Five mounting pins project from the underneath portion of the luggage lock as evidenced by FIGS. 2, 3 and 4.

I claim:

The ornamental design for a luggage lock or similar article, as shown and described.
